Diederheim & Furtner

UNITED STATES PATENT OFFICE.

HENRY H. FEFEL, OF PHILADELPHIA, PENNSYLVANIA, ASSIGNOR OF ONE-HALF TO THOMAS A. PEARCE, OF SAME PLACE.

SEWING-MACHINE.

SPECIFICATION forming part of Letters Patent No. 407,186, dated July 16, 1889.

Application filed August 30, 1888. Serial No. 284,115. (No model.)

To all whom it may concern:

Be it known that I, HENRY H. FEFEL, a citizen of the United States, residing in the city and county of Philadelphia, State of Pennsylvania, have invented a new and useful Improvement in Sewing-Machines, which improvement is fully set forth in the following specification and accompanying drawings.

10 My invention consists of improvements in sewing-machines, as hereinafter set forth and claimed.

Figure 1 represents a side elevation of a sewing-machine embodying my invention. 15 Fig. 2 represents a top plan view of a portion thereof. Fig. 3 represents an end elevation thereof, to clearly illustrate the location of the hook and looper with relation to the needle. Fig. 4 represents a detail view of the 20 hook, the main or driving shaft, and the mechanism for revolving the hook and shaft. Fig. 5 represents an enlarged view of the stitch formed by my machine.

Similar letters and numerals of reference 25 indicate corresponding parts in the several figures.

Referring to the drawings, A designates the bed-plate; B, the curved upright or goose-neck rising therefrom; C, the spring presser-30 foot carried by the upright; D, the cloth-plate; E, the vibrating lever; F, the needle-bar; G, the needle carried thereby; H, the link for operating the vibrating lever, and J the fly-wheel or driving-pulley.

35 The numeral 1 designates the main or driving shaft, which is mounted in the goose-neck or curved upright and carries a gear-wheel 2, meshing with a gear-wheel 3, the said gear-wheel 3 being mounted on a stud 4, carried 40 by a post or standard 5. The said meshing gear-wheels 2 and 3 are of the same size. The driving-shaft at one end is bored out or socketed at 6, forming a sleeve or barrel, and in said sleeve is placed a shaft 7, carrying a 45 hook 8. On the "hook-shaft," as it may be termed, is secured a gear-wheel 10, which meshes with a gear-wheel 10^x, mounted on the stud 4, and said gear-wheel 10^x is of a diameter twice as great as that of the gear-wheel 50 10, in consequence of which the hook-shaft is

revolved twice as rapidly as the driving-shaft, the purpose of which will appear. The feed-cam K is mounted on a sleeve K' rotatable on the shaft 7 by means of the pinion 2^x thereon, which meshes with the pinion 3^x 55 on the shaft 4. From this construction it will be observed that as the central gear-wheel 10^x has a diameter twice as great as that of the wheel 10 the hook-shaft is revolved twice as fast as the driving-shaft—or, in other words, 60 the hook revolves two to one of the driving-shaft, the purpose of which is to enable the hook to take the thread from the needle and looper, as will presently appear.

On the driving-shaft is secured a grooved 65 or cam wheel 11, which operates against the lower end of the vertical take-up lever 12, having an arm 13 pivoted thereto and extending above the needle, and having an eye therein to allow the passage of the needle-thread after it leaves the guide 14, as shown in Fig. 1.

16 designates the horizontal take-up lever for the looper, which is pivoted to a post or lug 17, and has its inner end in contact with 70 the cam or grooved wheel, and has an eye in its outer end through which the looper-thread passes after leaving the guide 18. From this construction it is evident that the cam or grooved wheel acts first upon one of the take-up levers and then upon the other, so as to take up the thread from the needle and looper 75 at the proper moment.

A bracket 19 is provided for the looper-spool, the thread of which passes through a 80 guide 20 on the bracket, and from thence to the guide 18.

21 designates an eccentric on the driving-shaft 22, a band encircling the same, and having an arm or pitman 23, connected with 85 the crank-shaft 24. The latter is journaled in boxes or bearings 25, attached to the feed-plate of the machine, and to the outer or front end of the shaft is connected one end of the link 26, connected to the lever 27, which is 90 fulcrumed on a stud 28 and carries the curved looper 29, having an eye through which the thread passes. From this construction it is evident that the eccentric on the driving-shaft imparts rocking motion to the crank- 95 100

shaft, in consequence of which the looper 29 is moved back and forth or given a sliding movement.

The operation is as follows: The driving-shaft is revolved and the reciprocating-needle descends, carrying its thread *a* through the material and forming the loop *b*. While the needle is descending the hook rotates and enters the loop formed thereby and spreads the same. The sliding looper approaches the revolving hook and passes through the needle-loop, and the hook revolves in time to take the thread *b* from the looper and enchain it with the needle-thread. It will thus be seen that the hook first takes the thread from the needle and spreads it, then takes the thread from the sliding looper and enchains it with the needle-thread, the hook releasing the needle-thread at the desired time and the take-up mechanism for the needle-thread and looper operating to take up the said threads at the proper time.

Having thus described my invention, what I claim as new, and desire to secure by Letters Patent, is—

1. In a sewing-machine, the combination, with the reciprocating needle, of the driving-shaft having a socket in one end, a shaft carrying the hook or looper fitted in said socket, 30 gearing on the driving and hook shafts, gearing meshing with said gearing for driving the hook and driving shafts at different speeds, and a sliding looper operating in conjunction with the needle and rotary hook or looper, substantially in the manner and for the purpose described.

2. In a sewing-machine, the combination, with the reciprocating needle, of the driving-shaft having one end socketed, said shaft also 40 carrying gearing, a hook-shaft carrying a

gear-wheel fitted in the socket of the driving-shaft, and gearing meshing with the gearing of the looper and driving-shaft for imparting different speeds thereto, substantially in the manner and for the purpose described.

45

3. In a sewing-machine, the combination, with the reciprocating needle, of a driving-shaft, a hook-shaft having a journal-bearing in said driving-shaft, a stud parallel with said driving and hook shafts, meshing gearing on 50 said driving and hook shafts and said stud, one of said gear-wheels on said stud being of twice the diameter of the meshing gear-wheel on the hook-shaft, substantially as and for the purpose set forth.

55

4. In a sewing-machine, the combination of a reciprocating needle, a driving-shaft and a hook-shaft carrying gear-wheels, a stud carrying a gear-wheel of different diameter from those on the driving-shaft and hook-shaft, 60 gear-wheels on the stud meshing with the gear-wheels on the driving and hook shafts, and a sliding looper operating in conjunction with the revolving looper and needle, substantially in the manner and for the purpose described.

65

5. In a sewing-machine, the combination of the driving-shaft carrying gear-wheels, a hook-shaft having a bearing in an end of said driving-shaft, a stud parallel with said shafts, meshing gearing on said shafts and stud, substantially as described, an eccentric on the driving-shaft, a band encircling the same and having an arm, a crank-shaft, a link, and a pivoted lever carrying a curved looper at one end, substantially as and for the purpose set forth.
